 Electric Laboratories, Inc., Chicago, Ill., a cor-
 poration of Delaware

Application April 18, 1938, Serial No. 202,662

27 Claims. (Cl. 179—81)

The present invention relates to telephone substation apparatus and has for one of its objects the provision of an improved arrangement for incorporating an auxiliary loud-speaking sound reproducing unit in a telephone substation circuit.

A substation of the character mentioned conventionally comprises a telephone transmitter and receiver, a hook or cradle switch, a ringing device and an auxiliary loud-speaking sound reproducing unit including amplifying means and arranged for alternative use with the telephone receiver. When the substation is to be used in a telephone system of the automatic type, there is also included in the circuit thereof a dial operated impulsing device for transmitting switch control impulses over the associated line to the automatic switching equipment provided in the line terminating exchange. In the improved substations of this type, anti-side-tone circuit or impedance networks are provided for preventing operation of the transmitter from effecting operation of the receiver when the receiver is connected for use and for preventing operation of the transmitter from effecting operation of the auxiliary sound reproducing unit when this unit is connected for use. Various substation arrangements of this character have, in the past, been used; and while, for the most part, these prior arrangements are reasonably satisfactory in operation, they are, in the usual instance, rather complicated in character and expensive.

It is another object of the present invention to provide an improved telephone substation circuit which is equipped alternatively to provide amplified or non-amplified reproduction of audio frequency currents transmitted to the substation, and which is of simple and economical arrangement and requires a minimum amount of circuit equipment.

It is a further object of the invention to provide in a substation circuit of the character mentioned a change-over relay operative to alter the substation circuit arrangement so that amplified or non-amplified reproduction of received audio frequency currents may selectively be obtained and which is also operative to cause a biasing voltage to be impressed between the input electrodes of one or more of the amplifier vacuum tubes included in the substation circuit.

It is a still further and more specific object of the invention to provide a telephone substation circuit including an anti-side-tone impedance network and apparatus for optionally providing amplified or non-amplified audio frequency output currents from the substation circuit.

which is so arranged that current for energizing the transmitter is fed to the substation transmitter over the line extending to the substation and audio frequency energy developed by operation of the transmitter is not delivered to the line through the current feed circuit. 5

In the illustrated embodiment of the invention the substation circuit is shown as comprising a transmitter, a receiver, and an anti-side-tone impedance network arranged to be interconnected to form a substation circuit. The anti-side-tone impedance network includes a plurality of inductively coupled impedance elements connected to form a four-arm bridge circuit and is operative, when the receiver is connected in 15 the substation circuit, to prevent audio frequency energy developed by operation of the transmitter from being delivered to the receiver. Also included in the substation is an auxiliary sound reproducing unit and a change-over relay which 20 is operative to substitute the auxiliary sound reproducing unit for the receiver in the substation circuit. A second amplifier is provided which, in combination with the anti-side-tone impedance network, functions to deliver audio 25 frequency energy developed through operation of the transmitter to the line extending to the line terminating exchange. In accordance with one feature of the present invention, the change-over relay, which operates to substitute the auxiliary sound reproducing unit for the receiver in the substation circuit, is also operative to impress a biasing voltage between the input electrodes of at least one vacuum tube included in each of the two amplifiers. More particularly, 30 power supply apparatus including a power rectifier is provided for delivering energy to each of the two amplifiers, which apparatus includes an input circuit arranged to be completed in response to the operation of a manually operable 35 switch. The change-over relay includes a winding connected and arranged to be energized in response to the completion of the power apparatus input circuit, and circuits are provided, individual to the amplifier tubes and commonly 40 including the relay winding, for impressing a biasing voltage between the input electrodes of each of the amplifier tubes. In accordance with another feature of the present invention, a circuit including a portion of the impedance elements embodied in the anti-side-tone impedance networks and the conductors of the line incoming to the substation circuit, is provided for conducting energizing current by way of the line to 45 the substation transmitter. This circuit includes 50 55

a network for effectively short-circuiting the current feed circuit for audio frequency currents developed by operation of the transmitter, thus preventing audio frequency energy from being delivered to the line by way of the current feed circuit and effectively providing a closed, low impedance, voice frequency transmission circuit.

Further features of the invention pertain to the particular arrangement of the circuit elements whereby the above and additional operating features of the circuit are attained.

The novel features believed to be characteristic of the invention are set forth with particularity in the appended claims. The invention, both as to its organization and method of operation, together with further objects and advantages thereof, will best be understood by reference to the specification taken in connection with the accompanying drawing in which there is illustrated in partially schematic form an automatic telephone system having incorporated therein a substation connected and arranged in accordance with the present invention.

Referring now to the single figure of the drawing, there is diagrammatically illustrated a telephone system comprising an automatic telephone exchange 10 which may, if desired, constitute a private automatic exchange. Terminating at the exchange 10 are a plurality of telephone lines, two of which are indicated at 11 and 12. The ends of the lines remote from the exchange 10 terminate in substations of the automatic type, that associated with the line 11 being diagrammatically illustrated at A, and that associated with the line 12 being indicated generally at B. The automatic exchange 10 comprises the usual subscriber controlled automatic switches for setting up connections between the telephone lines of the system. More particularly, these switches are, in accordance with conventional practice, divided into two classes, namely, non-numerical switches such, for example, as line finder or line switches, and numerical switches, such, for example, as selector and connector switches, which are responsive to impulses transmitted thereto over calling ones of the telephone lines and function to perform the usual line group, subgroup and unit selecting operations. The connector switches at which the lines terminate are, in accordance with conventional practice, equipped to perform the usual auxiliary functions of: testing a selected called line to determine the idle or busy condition thereof, returning busy tone over the calling line in the event a selected called line is found busy, and projecting ringing current over a selected called line to actuate the signal device at the called substation in the event a selected called line is idle at the time it is tested.

Referring now more particularly to the equipment provided at the substation B, this equipment comprises a ringing or signal device 13 connected across the line conductors 16 and 17 of the line 12 in series with a condenser 15, a transmitter 18, a receiver 19, an impulsing device 20, and switching means in the form of a hook or cradle switch 21. The transmitter and receiver preferably are mounted as a unit to form a hand set of the usual type. The switch 21 comprises a member 22 for supporting the receiver 19 when not in use and switch springs 23 and 24 of which the springs 23 are operative in response to the removal of the receiver 19 from the supporting member 22, to place a direct current bridge across the conductors of the line 12, thereby to

create a calling condition on this line and operatively to include the receiver 19 in the substation circuit. The impulsing device 20 is of the conventional dial operated type and comprises a pair of impulsing springs 25 and a set of shunt springs 26, which latter springs are normally restrained to the open circuit position indicated in the drawing and are so arranged that the dial mechanism closes the same during operation of the impulsing device. Also included in the substation circuit is an auxiliary sound reproducing unit comprising a translating device or loud speaker 27 coupled to the output electrodes of a vacuum tube amplifier including a vacuum tube 28 of the well-known pentode type. More particularly, the input terminals of the loud speaker 27 are connected to the secondary winding of a coupling transformer 29 having a primary winding connected between the anode 30 and the cathode 31 of the tube 28 in series with a source of anode potential comprising the power supply apparatus described more particularly hereinafter. The vacuum tube 28 also includes input electrodes comprising a cathode 31 and a control grid which are coupled to the adjustable portion of a voltage dividing resistor 32.

Incoming signal currents are delivered to the receiver 19 or to the auxiliary sound reproducing unit through an anti-side-tone impedance network indicated generally at 33. This network comprises a plurality of impedance elements 34, 35, 36, 37 and 38 which are inductively coupled to each other in the manner illustrated. The first four of the enumerated elements are interconnected to form a bridge circuit having conjugate terminals between which is connected the secondary winding 39 of a coupling transformer 40, the arrangement being such that currents traversing the secondary winding 39 divide and traverse the two arms 34 and 35 of the bridge in opposite directions. The winding 38, which is arranged to be coupled to the receiver 19 or to the input terminals of the auxiliary sound reproducing unit, is so coupled to the two windings 34 and 35 that, when alternating currents of equal magnitude and opposite phase traverse these two windings, substantially no voltage is developed between the terminals of the winding 38. For the purpose of balancing the equivalent impedances, measured at the terminals of the substation B, of the impedance elements external to this substation when the substation is involved in an established communication connection, there is provided a balancing network comprising a condenser 41 and an adjustable resistor 42. More particularly, these two elements are suitably proportioned to balance the equivalent impedance of: the shunt and series impedances of the line 12, the impedances of the coupling elements included in an established switch train, the shunt and series impedances of a second line connected through the established switch train to the line 12, and the impedances of the circuit elements included in a substation circuit connected to the second line.

The transformer 40 is provided with a primary winding 43 to which the transmitter 18 is normally coupled by means of a coupling transformer 44 including a primary winding 45 and a secondary winding 46. For the purpose of amplifying audio frequency currents developed by operation of the transmitter 18, there is provided a second amplifier which includes a vacuum tube 47 of the well-known pentode type. 75

More particularly, the vacuum tube 47 is provided with output electrodes comprising an anode 48 and a cathode 49 which are arranged to be connected directly across a series circuit including the transformer winding 43 and the source of anode potential comprising the power supply apparatus described hereinafter. The tube 47 also includes input electrodes comprising the cathode 49 and a control grid 50. These electrodes are coupled to the adjustable portion of a voltage dividing resistor 51 shunting the secondary winding 46 of the coupling transformer 44.

The above-described outgoing signal current amplifier is provided in order to permit the transmitter 18 to be used as the microphone irrespective of which of the translating devices 19 and 27 is used as the receiving means. In this regard and as pointed out in detail hereinabove, when the auxiliary sound reproducing unit including the loud speaker 27 is operatively included in the substation circuit, the hand set comprising the transmitter 18 and the receiver 19 is not removed from the supporting cradle 22. This means that a person must speak into the transmitter from a distance when the receiver is not being used. Hence, the outgoing signal amplifier is required to step up the level of the audio energy delivered to the line 12 during operation of the transmitter and when the hand set including the transmitter is not removed from its cradle.

The arrangement is such that current for energizing the transmitter 18 is conducted from the exchange battery provided in the exchange 10 by way of the windings of the line relay embodied in an operated one of the numerical switches also included in the exchange 10, the line conductors 16 and 17 of the line 12 and the two inductance elements 34 and 37 of the network 33 to the transmitter 18. In order to prevent audio frequency energy developed by operation of the transmitter 18 from being delivered over the circuit just described to the line 12, there is provided an audio frequency current blocking and by-pass network comprising a choke coil 52 and two by-pass condensers 53 and 54 individually having capacitance values such that the impedance thereof to audio frequency currents is exceedingly low.

The power supply apparatus, mentioned above, includes a voltage step-down transformer 55 having a primary winding 56 included in the input circuit for the apparatus, which circuit also comprises a source of alternating current, not shown, but arranged to be connected between the input terminals 57. The transformer 55 also includes a low voltage secondary winding 58 for supplying energizing current to the cathode heaters of the two vacuum tubes 28 and 47, a low voltage secondary winding 59 for energizing a signal lamp 60 when the transformer primary winding 56 is energized, and a low voltage winding 61 for energizing the cathode heater 62 of a full wave rectifying tube 62. The vacuum tubes 28, 47 and 62 are preferably of the type embodying directly heated cathodes for the reason that a tube of this type inherently requires less time for its cathode to reach its normal electron emitting temperature following the energization of the cathode heater. The tube 62 is provided with a pair of anodes 63 and 64 connected to opposite terminals of a high voltage secondary winding 65 embodied in the transformer 55 and having its output center point

brought out to a conductor 66 which forms the negative side of the rectifier output voltage. For the purpose of smoothing the rectified output voltage of the tube 62, there is provided a network which comprises two choke coils 67 and 68 and three condensers 69, 70 and 71 connected in the manner illustrated to form a conventional filter circuit.

In order to substitute the auxiliary sound reproducing unit for the receiver 19 in the substation circuit and for the additional purpose of operatively including the signal amplifier comprising the vacuum tube 47 in the path for delivering audio frequency energy from the transmitter 18 to the line 12, there is provided a relay 10 72 which includes a winding arranged to be energized in response to the completion of the input circuit to the power supply apparatus. More particularly, this relay includes a winding connected in series with the resistor 73 between the negative power supply conductor 66 and the center tap of the low voltage secondary winding 58. The series connected resistor 73 and winding of the relay 72 are by-passed for audio frequency currents by a condenser 74. With the 25 winding of the relay 72 connected in this manner, it will be noted that this relay is operative to impress a biasing voltage between the input electrodes of each of the two tubes 28 and 47. More particularly, the voltage drop developed across the resistor 73 and the winding of the relay 72 when this winding is energized is impressed between the cathode and control grids of each of the two tubes noted to drive the cathodes of the respective tubes positive with respect to their 35 respective associated control grids. The resistor 73 is provided for the purpose of permitting a relay of standard construction and having a fixed resistance to be used, while providing the requisite biasing voltage for the input electrodes of 40 the two tubes 28 and 47.

The relay 72 is provided with a pair of armatures 75 and 76, the first of which cooperates with an associated contact 77 and is operative from resting engagement with this contact to 45 disconnect the receiver 19 from the substation circuit and operatively to include the auxiliary sound reproducing unit in this circuit. The second armature 75 is operative between a resting contact 78 and a working contact 79 to include 50 the second amplifier comprising the vacuum tube 47 in the path for transmitting audio frequency energy from the transmitter 18 to the line 12. More particularly, the armature 75 normally engages the resting contact 78 so that the amplifier tube 47 is excluded from the transmission path noted, the transmitter 18 normally being coupled to a closed link circuit comprising the secondary winding 46 of the coupling transformer 44, a condenser 80, and the secondary 60 winding 43 of the transformer 40. When, however, the relay 72 is energized, this link circuit is interrupted and the output electrodes of the tube 47 are connected across the winding 43 of the transformer 40, it being observed that the 65 input electrodes of this tube are at all times coupled to the adjustable portion of the voltage dividing resistor 51.

For the purpose of preventing the substation circuit from singing, due to electrical and acoustical coupling between the energy receiving and energy transmitting channels, there is provided a relatively large condenser 81 which is arranged effectively to short-circuit the transmitter 18, during intervals when the network 33 is unbal- 75

anced. In order to complete the input circuit to the power supply apparatus and to place a bridging path across the conductors 16 and 17 of the line 12 independently of the hook or cradle switch 21, there is provided a key operated calling switch 82 which includes two sets of switch springs 83 and 84. There is also provided a key operated answer switch 85 including a pair of springs 86 which are operative to open the low impedance circuit including the condenser 81 normally shunting the transmitter 18, thereby to condition the substation circuit for operation. The two key operated switches 82 and 85 are of the locking type, and means comprising a suitable mechanical interlock, indicated by the dotted line 81, are provided, whereby the switch 82 may be operated to the off-normal position without affecting the position of the switch 85, the switch 82 is operated to its off-normal position in response to operation of the switch 85 to the off-normal position, and both switches are simultaneously restored to normal in response to the operation of the switch 85 to its normal position. More particularly, the switch 82 is operative to its off-normal position to close the two sets of springs 83 and 84 without operating the switch 85 to its off-normal position. Operation of the switch 85 to its off-normal position, however, causes the switch 82 to be operated to its off-normal position. With both of the switches operated to the off-normal position, and when the switch 85 is returned to normal, the mechanical interlock functions to cause the switch 82 also to be restored to its normal position.

Referring now to the operation of the system and assuming, for example, that a call is initiated at the substation A and routed by way of the automatic switching equipment provided in the exchange 10 and the line 12 to the substation B at a time when the last-mentioned substation is idle, when the line 12 is seized by one of the connector switches provided at the exchange 10 and tests idle, ringing current is projected over the called line to actuate the ringing device 13, thereby to give an audible indication that the substation B is being called. The party answering the call has the option of employing the receiver 19 or the auxiliary sound reproducing unit to transform incoming audio frequency currents into sound energy. If the party answering the call elects to employ the receiver 19 as the sound reproducing means, this receiver is removed from its supporting member 22 in the usual manner. The hook switch 21 responds to this operation by closing its contact springs 23 and opening its contact springs 24. At the springs 24, the low impedance shunt comprising the condenser 81 normally connected across the transmitter 18 is interrupted. At the springs 23, a direct current bridging path is completed between the conductors of the line 12, this path extending from the line conductor 16 by way of the inductance element 34, the transmitter 18, the transformer winding 45, the choke coil 52, the transformer winding 39, the inductance element 37, the impulsive springs 25 and the closed springs 23 to the opposite line conductor 17. The completion of this bridging path results in the operation of the connector switch to arrest the ringing operation and to complete a talking connection between the calling and called substations in the usual manner.

When the talking connection is completed, the exchange battery provided in the exchange 10 is connected between the line conductors 16 and 17

in series with the windings of the back bridge relay conventionally provided in the operated connector switch, so that current for energizing the transmitter 18 is delivered by way of the line conductors 16 and 17 and through the two inductance elements 34 and 37 to the transmitter circuit in the manner pointed out above. This transmitter circuit is effectively closed and comprises the primary winding 45 of the coupling transformer 44 and the low impedance by-pass condenser 53. Due to the low impedance of this condenser, the low impedance of the condenser 54, and the high impedance of the choke coil 52 to audio frequency currents, substantially no audio frequency energy is fed back over the transmitter energizing circuit and through the two inductance elements 34 and 37 of the network 33 to the line 12. The purpose of preventing such feed-back of energy and of providing the low impedance path comprising the condenser 53 is to increase the transmitting efficiency of the transmitter 18. More particularly, if all of the impedances included in the circuit over which direct energizing circuit is supplied to the transmitter 18 were connected in series with this transmitter, very little audio voltage would be developed across the primary winding 45 of the transformer 44, and the transmitting efficiency of the substation circuit would be very poor. By virtue of the provision of the audio frequency by-passing and blocking network comprising the three elements 52, 53 and 54 substantially the full audio frequency voltage developed by operation of the transmitter 18 is impressed across the terminals of the transformer primary winding 45.

With the key operated answer switch 85 in its normal position, audio frequency currents traversing the transformer winding 45 produce corresponding induced voltages in the secondary winding 46 which cause corresponding currents to flow in the closed link circuit comprising the winding 46, the condenser 80, the resting contact 18 and armature 75 of the relay 72, the primary winding 43 of the coupling transformer 40 and the condenser 71. These currents cause corresponding induced voltages to be developed in the secondary winding 39 which are impressed on the conjugate terminals of the anti-side-tone bridge through the condenser 54. The currents produced as an incident of these induced voltages divide between the inductance elements 34 and 35, substantially one-half of the current traversing a path extending by way of the inductance element 35, the condenser 41, the resistor 42, and the inductance element 36, and the other half of the current traversing the inductance element 34, the loop extending through the automatic exchange 10 to the substation A, and the inductance element 37. Through the provision of the balancing network comprising the condenser 41 and the resistor 42, the currents respectively traversing the inductance elements 34 and 35 are rendered substantially equal in magnitude and opposite in phase at all frequencies within the operating band. Since the inductance element 38 is substantially equally energized by the currents of equal magnitude traversing the two elements 34 and 35, substantially no audio frequency voltage is developed across the terminals of the element 38 during operation of the transmitter. Thus, the well-known anti-side-tone effect is realized.

The path traversed by voice frequency currents incoming to the substation B extends from the line conductor 16 by way of the two inductance

elements 34 and 35, the condenser 41, the resistor 42, the two inductance elements 36 and 37, the impulsive springs 25 and the switch springs 23 to the opposite line conductor 17. Obviously, portions of the incoming currents are by-passed around the two elements 35 and 36 through the branch circuit comprising the condenser 41 and the secondary winding 39. In this case the currents traversing the two elements 34 and 35 are in aiding phase relation so that substantial corresponding voltages are developed across the terminals of the element 38 which are impressed across the receiver 19 over a circuit including the armature 16 and the associated resting contact 11 of the relay 12.

In the event the answering party elects to employ the auxiliary sound reproducing unit as the receiving means, the receiver 19 is retained on its supporting member 22 and the key operated answer switch 85 is operated to its off-normal position to open the springs 86, thereby to interrupt the low impedance path comprising the condenser 81 normally shunting the transmitter 18. Due to the above-described mechanical interlock between the two switches 85 and 82, the switch 82 is also operated to its off-normal position in response to the operation of the switch 85 to its off-normal position. Thus, the springs 83 and 84 are closed when the switch 85 is operated to its off-normal position. At the springs 83, the input circuit to the power supply apparatus is completed and, at the springs 84, the bridging path, traced above, is completed between the line conductors 16 and 17, whereby the operated connector switch in the exchange 10 is caused to operate to interrupt the ringing operation, to complete the talking connection between the calling and called substations, and to impress talking battery voltage between the conductors 16 and 17 of the line 12. In response to the completion of the input circuit to the power supply apparatus, the various secondary windings of the transformer 55 are energized, whereby energizing current is delivered to the cathode heaters respectively embodied in the tubes 28, 41 and 62, and anode voltage is developed between the positive and negative output conductors of the rectifier to supply anode and screen potentials to each of the two tubes 28 and 41. Thus, the two amplifiers comprising, respectively, the tubes 28 and 41, are conditioned for operation. When the secondary winding 59 is energized, energizing current is delivered to the signal lamp 60, thus causing this lamp to give a visual indication that the answer switch 85 occupies its off-normal position.

It will be observed that the winding of the relay 12 is included in the cathode leg of the output circuit for the tube 28, so that, when anode current starts to flow in this circuit, the relay 12 operates to interrupt, at the armature 16 and its associated resting contact 11, the above-traced circuit for conducting incoming audio frequency currents to the receiver 19. Normally, this circuit is shunted across the non-adjustable terminals of the potentiometer resistor 32. When the relay 12 operates, however, the shunting path including the receiver 19 is interrupted so that the audio voltage developed across the inductance element 38 causes a current to traverse only the resistor 32. The portion of this voltage developed across the adjustable portion of the resistor 32 is impressed between the input electrodes of the tube 28, is amplified in this tube, and the amplified audio ener-

gy is delivered through the coupling transformer 29 to the loud speaker 27 for reproduction. It is noted that the resistance of the resistor 32 is chosen to have a value of the order of 100,000 ohms which is relatively high as compared to the highest impedance of the receiver 19, whereby this resistor does not by-pass or shunt from the receiver 19 any substantial portion of the audio energy when the receiver is operatively included in the circuit and the signal amplifier of the auxiliary sound reproducing unit is inactive.

The relay 12, upon operating, not only substitutes the auxiliary sound reproducing unit for the receiver 19 in the substation circuit, but also operatively includes the second amplifier comprising the vacuum tube 47 in the channel for transmitting audio frequency energy from the transmitter 18 to the line 12. More particularly, when the relay 12 operates, it interrupts, at the armature 15 and its associated resting contact 19, the above-traced closed link circuit including the condenser 80 and connects, at the armature 15 and its associated working contact 19, the output electrodes of the tube 47 directly across the primary winding 43 connected in series with the source of anode voltage. As indicated above, the input electrodes of the tube 47 are permanently coupled across the adjustable portion of the potentiometer resistor 51 so that, when the tube 47 is energized, it is conditioned to amplify the audio voltage appearing across the indicated portion of the resistor 51. With the relay 12 operated, the amplifier tube 47 delivers its amplified audio output by way of the coupling transformer 40 and the anti-side-tone impedance network 33 to the line 12. It is pointed out that the resistance of the potentiometer resistor 51 is relatively high, being of the order of 100,000 ohms. Also, when the vacuum tube 47 is inactive, the admittance between the input electrodes 49 and 50 thereof is exceptionally low. Thus, only a small portion of the audio frequency energy developed by operation of the transmitter 18 is dissipated in the resistor 51 and the tube 47.

It will be noted that when the power supply apparatus is energized, the winding of the relay 12 is initially energized only by the current traversing the cathode leg of the output circuit for the tube 28. Thus, until the relay 12 operates, the output circuit for the tube 47 is held open at the armature 15 and its associated working contact 19. This means that a relatively low biasing voltage is initially impressed between the input electrodes of the tube 28 and, hence, the anode current of this tube 28, which current traverses the winding of the relay 12, is relatively large. When the relay 12 operates, the output circuit for the tube 47 is completed in the manner pointed out above, so that the current traversing the winding of the relay 12 is the sum of the anode currents flowing through the tubes 28 and 47. Thus, following operation of the relay 12, the biasing voltage impressed between the input electrodes of each of the tubes 28 and 47 is determined by the magnitude of the sum of the anode currents respectively flowing through the two tubes.

When the conversation is terminated and the connection is released, the switch 85 is restored to its normal position to recomplete, at the springs 86, the above-traced low impedance path comprising the condenser 81 for shunting the transmitter 18. Due to the above-described mechanical interlock between the switches 82 and 85, the switch 82 is also restored to normal in

response to the operation of the switch 85 to its normal position. When the switch 82 is returned to normal, the springs 83 and 84 are opened respectively to interrupt the input circuit to the power supply apparatus and the bridging path between the conductors of the line 12. If the answering party fails to restore the switch 85 to normal, the energized condition of the lamp 60 is a visual reminder that the substation B is still 10 operatively connected to the line 12. Obviously, when the circuit to the power supply apparatus is interrupted, current is no longer supplied to the cathode heaters of the tubes 28, 47 and 62, and the two signal amplifiers are rendered inactive. 15 The resulting deenergization of the winding of the relay 72 causes this relay operatively to include the receiver 19 in the substation circuit and effectively to exclude the auxiliary sound reproducing unit from the circuit. At the armature 75 and its associated working contact 79, the relay 72 disconnects the output electrodes of the tube 47 from across the primary winding 43 of the transformer 40 and, at the armature 75 and its associated resting contact 78, the relay 72 20 recompletes the above-traced link circuit including the condenser 80. Thus, the substation apparatus is restored to normal. 25 If the receiver 19 is utilized as the receiving means, this receiver is restored to its supporting member 22 at the conclusion of the conversation in the usual manner, whereby the hook or cradle switch 21 is restored to its normal position. When the switch 21 is restored to normal, the springs 23 are opened to interrupt the bridging 30 path between the conductors of the line 12 and the springs 24 are closed to connect the low impedance condenser 81 in shunt with the transmitter 18. It will be apparent from the foregoing description that the auxiliary sound reproducing unit and the receiver 19 may alternately 35 be used as the receiving means during a single conversation by the simple expedient of operating the answer switch 85 from its normal to its off-normal position and vice versa. 40 45 In order to initiate a call at the substation B, intended for one of the other substations, such, for example, as the substation A, the calling party may optionally use the regular substation transmitter and receiver or the auxiliary equipment comprising the auxiliary sound reproducing unit and the amplifier for amplifying audio frequency currents outgoing from the substation. If the calling party elects to use the receiver 19 50 as the receiving means, this receiver is removed from its supporting member 22 to cause the hook switch 21 to be operated to its off-normal position, whereby the above-described bridging path 55 between the conductors of the line 12 is completed to complete a loop circuit extending to the automatic switching equipment provided in the exchange 10. At the springs 24, the above-traced low impedance path shunting the transmitter 18 and comprising the condenser 81, is interrupted. When the loop circuit, including 60 the two conductors of the line 12, is completed to the exchange 10, an associated or assigned non-numerical switch provided in the exchange is caused to operate in the usual manner to extend the calling loop circuit through to one of 65 the non-numerical switches, which latter switch functions to return dial tone over the established loop to the calling party. It will be noted that the impulsive springs 25 of the impulsive device 20 are serially included in the loop circuit extending to the operated switch train. During 70 75

operation of the impulsive device, the impulsive springs 25 are alternately opened and closed in the usual manner, thereby to transmit impulses by way of the line 12 to the seized automatic switching equipment in the exchange 10. This equipment responds to the impulses in the usual manner to cause the connection to be forwarded by way thereof to the called line 11. During each operation of the impulsive device 20 or, more particularly, during each digit dialed at the 10 substation B, the shunt springs 26 are closed to complete an obvious path for excluding the substation apparatus from the impulsive circuit. When the operation of the impulsive device 20 is ended, the shunt springs 26 are opened in the 15 usual manner, thereby to condition the substation circuit for voice frequency current transmission and reception. In this connection, it will be apparent that, if the selected called line 11 is tested and found busy, busy-tone current is returned over the calling loop circuit to be reproduced by the receiver 19. If, on the other hand, the called line is idle and ringing current is projected thereover to signal the called party, ring-back-tone current is conducted over the calling line and through the resistor 19 to indicate that the called substation is being rung. When the calling subscriber answers, the desired conversational connection is completed in the usual manner. Following the completion of the connection, the paths traversed by the signal currents incoming and outgoing from the substation B are identical with those traced above. 20 25 30 35 40 45 50 55 60 65 70 75 80 85 90 95 100

In the event the calling party elects to use the auxiliary substation equipment, namely, the auxiliary sound reproducing unit and the outgoing signal amplifier comprising the vacuum tube 47, the receiver 19 is not removed from its supporting member 22, but the calling key switch 82 is operated to its off-normal position to close the 40 springs 83 and 84. At the springs 84, the above-traced bridging path between the conductors of the line 12 is completed and, at the springs 83, the input circuit to the power supply apparatus is completed. Thus, the two signal amplifiers are conditioned for operation, the relay 72 is caused to operate to exclude the receiver 19 from the substation circuit and operatively to include the auxiliary sound reproducing unit in the circuit, and a non-numerical switch provided in the exchange 10 is caused to operate to extend the calling loop circuit through to a selected one of the numerical or impulse responsive switches. As indicated above, the mechanical interlock between the two key operated switches 82 and 85 is such that the last-mentioned key is not operated to its off-normal position in response to the operation of the key 82 to its off-normal position. Hence, the springs 86 are retained in engagement to hold completed 60 the low impedance path shunting the transmitter 18. The purpose of this path is to prevent the substation apparatus from singing or oscillating locally during the period of unbalance of the anti-side-tone impedance network 33. 65 More particularly, when the call is initiated and until the call is answered at the called substation, the impedance provided by the series connected condenser 41 and resistor 42 is not balanced by the equivalent impedance, measured 70 at the substation terminals between the line conductors 16 and 17, of the impedances associated with the line 12 and external to the substation B. Thus, the anti-side-tone impedance network is unbalanced and electrical coupling is inad- 75

vertently provided between the output circuit of the signal amplifier comprising the tube 47 and the input circuit of the signaling amplifier comprising the tube 28. Also, acoustical coupling exists between the loud speaker 27 and the transmitter 18. By virtue of these two couplings, a closed, local oscillatory circuit comprising the two signal amplifiers, the loud speaker 27 and the transmitter 18, is created during the interval 10 when the anti-side-tone network is unbalanced. Through the provision of the low impedance path shunting the transmitter 18 and comprising the condenser 81, however, this local circuit is effectively interrupted because substantially no 15 input energy can be delivered to the signal amplifier comprising the vacuum tube 47. Hence, the system is prevented from oscillating, and singing or howling is minimized.

Following the operation of the switch 82 to 20 its off-normal position, the connection is routed by way of the automatic switching equipment provided in the exchange 10 to the called line 11 in response to operation of the impulsing device 20 in the exact manner described above. 25 When the call is answered at the called substation A, the desired conversational circuit is completed, and the anti-side-tone impedance network 33 is balanced, so that the electrical coupling as described above and included in the 30 local substation circuit is substantially eliminated. Obviously, when the call is answered, incoming audio frequency currents are reproduced by the auxiliary sound reproducing unit even though the transmitter 18 is effectively shunted by the 35 low impedance path described above. When the call is answered, the calling party may condition the substation circuit for the transmission of audio frequency currents therefrom by operating the answer switch 85 to its off-normal position, 40 thereby to interrupt, at the springs 86, the low impedance path shunting the transmitter 18.

In order to release the connection, as established in the above-described manner, after the conversation is terminated, it is only necessary 45 for the calling party to return the receiver 19 to its supporting member 22 or to operate the answer key 85 to its normal position, depending upon whether the receiver 19 is utilized as the 50 receiving means or whether the auxiliary sound reproducing unit is used for reproducing incoming audio frequency currents. The response of the apparatus when either of these two operations is performed is exactly the same as that set forth above with respect to a call incoming 55 to the substation B.

While there has been described what is at present considered to be the preferred embodiment of the invention, it will be understood that various modifications may be made therein, and 60 it is intended to cover in the appended claims all such modifications as fall within the true spirit and scope of the invention.

What is claimed is:

1. A telephone substation adapted to be connected to a telephone line comprising a pair of conductors arranged to have a source of direct current connected thereto and comprising, in combination, a transmitter, a sound reproducing device and an anti-side-tone impedance network arranged to be interconnected to form a substation circuit, said anti-side-tone impedance network comprising a plurality of impedance elements and being operative to prevent audio frequency energy developed by operation of said 70 transmitter from being delivered to said sound 75

reproducing device, a circuit including a portion of said impedance elements and the conductors of said line for conducting energizing current from said source to said transmitter, said circuit also including a network for preventing 5 audio frequency energy developed by operation of said transmitter from being delivered to said line over said circuit, an auxiliary sound reproducing unit comprising an amplifier, said amplifier comprising a vacuum tube having input electrodes, a second amplifier including a vacuum tube having input electrodes, a relay operative to substitute said auxiliary sound reproducing unit for said sound reproducing device in said substation circuit, said relay also being 10 operative to include said second amplifier in said substation circuit, means including said second amplifier and said anti-side-tone impedance network for delivering audio frequency energy developed by operation of said transmitter to said line, and means including said relay for impressing a biasing voltage between the input electrodes of at least one of said tubes.

2. A telephone substation adapted to be connected to a telephone line comprising a pair of conductors arranged to have a source of direct current connected thereto and comprising, in combination, a transmitter, a sound reproducing device and an anti-side-tone impedance network arranged to be interconnected to form a 25 substation circuit, said anti-side-tone impedance network comprising a plurality of impedance elements and being operative to prevent audio frequency energy developed by operation of said transmitter from being delivered to said sound 30 reproducing device, a circuit including a portion of said impedance elements and the conductors of said line for conducting energizing current from said source to said transmitter, said circuit also including a network for preventing 35 audio frequency energy developed by operation of said transmitter from being delivered to said line over said circuit, an auxiliary sound reproducing unit comprising an amplifier, said amplifier comprising a vacuum tube having input electrodes, a 40 second amplifier including a vacuum tube having input electrodes, a relay operative to substitute said auxiliary sound reproducing unit for said sound reproducing device in said substation circuit, said relay also being operative to include said second 45 amplifier in said substation circuit, means including said second amplifier and said anti-side-tone impedance network for delivering audio frequency energy developed by operation of said transmitter to said line, said relay having a winding, and circuits individual to said tubes and 50 commonly including said winding for impressing a biasing voltage between the input electrodes of each of said tubes.

3. A telephone substation adapted to be connected to a telephone line comprising a pair of conductors arranged to have a source of direct current connected thereto and comprising, in combination, a transmitter, a sound reproducing device and an anti-side-tone impedance network 65 arranged to be interconnected to form a substation circuit, said anti-side-tone impedance network comprising a plurality of impedance elements and being operative to prevent audio frequency energy developed by operation of said 70 transmitter from being delivered to said sound reproducing device, a circuit including a portion of said impedance elements and the conductors of said line for conducting energizing current from said source to said transmitter, said circuit 75

- also including a network for preventing audio frequency energy developed by operation of said transmitter from being delivered to said line over said circuit, an auxiliary sound reproducing unit comprising an amplifier, said amplifier comprising a vacuum tube having input electrodes, a second amplifier including a vacuum tube having input electrodes, a relay operative to substitute said auxiliary sound reproducing unit for said sound reproducing device in said substation circuit, said relay also being operative to include said second amplifier in said substation circuit, means including said second amplifier and said anti-side-tone impedance network for delivering 10 audio frequency energy developed by operation of said transmitter to said line, power supply apparatus including an input circuit, a switch operable to complete said input circuit, said relay including a winding connected and arranged to be energized in response to the completion of said input circuit, and circuits individual to said tubes and commonly including said winding for impressing a biasing voltage between the input electrodes of each of said tubes.

5 4. A telephone substation adapted to be connected to a telephone line comprising a pair of conductors arranged to have a source of direct current connected thereto and comprising, in combination, a transmitter, a sound reproducing 15 device and an anti-side-tone impedance network arranged to be interconnected to form a substation circuit, said anti-side-tone impedance network comprising four coupled inductance elements connected to form a bridge including four 20 arms and two conjugate terminals, a transformer including a primary winding normally coupled to said transmitter and a secondary winding coupled to said conjugate terminals, whereby currents traversing said secondary winding divide and traverse two of the arms of said bridge in opposite directions, said anti-side-tone impedance network including another inductance element inductively coupled to said two arms of said bridge and normally coupled to said sound reproducing device, whereby audio frequency energy developed by operation of said transmitter is not delivered to said sound reproducing device, 25 a circuit including two arms of said bridge and the conductors of said line for conducting energizing current from said source to said transmitter, said last-named circuit also including a network for preventing audio frequency energy developed by operation of said transmitter from being delivered to said line over said last-named circuit, an auxiliary sound reproducing unit including an amplifier, said amplifier comprising a vacuum tube having input electrodes, a second 30 amplifier having output terminals and including a vacuum tube having input electrodes coupled to said transmitter, a relay operative to substitute said auxiliary sound reproducing unit for said sound reproducing device in said substation circuit, said relay also being operative to couple the output terminals of said second amplifier to the primary winding of said transformer, whereby said second amplifier and said anti-side-tone impedance network are conditioned to deliver 35 audio frequency energy developed by operation of said transmitter to said line, said relay having a winding, and circuits individual to said tubes and commonly including said winding for impressing a biasing voltage between the input electrodes of each of said tubes.

40 5. A telephone substation adapted to be connected to a telephone line comprising a pair of conductors arranged to have a source of direct current connected thereto and comprising, in combination, a transmitter, a sound reproducing device and an anti-side-tone impedance network including another inductance element inductively coupled to said two arms of said bridge and normally coupled to said sound reproducing device, whereby audio frequency energy developed by operation of said transmitter is not delivered to said sound reproducing device, a circuit including two arms of said bridge and the conductors of said line for conducting energizing current from said source to said transmitter, said last-named circuit also including a network for preventing audio frequency energy developed by operation of said transmitter from being delivered to said line over said last-named circuit, an auxiliary sound reproducing unit including an amplifier, said amplifier comprising a vacuum tube having input electrodes, a second 45 amplifier having output terminals and including a vacuum tube having input electrodes coupled to said transmitter, a relay operative to substitute said auxiliary sound reproducing unit for said sound reproducing device in said substation circuit, said relay also being operative to couple the output terminals of said second amplifier to the primary winding of said transformer, whereby said second amplifier and said anti-side-tone impedance network are conditioned to deliver 50 audio frequency energy developed by operation of said transmitter to said line, said relay having a winding, and circuits individual to said tubes and commonly including said winding for impressing a biasing voltage between the input electrodes of each of said tubes.

55 6. A telephone substation adapted to be connected to a telephone line comprising a pair of conductors arranged to have a source of direct current connected thereto and comprising, in combination, a transmitter, a sound reproducing device and an anti-side-tone impedance network arranged to be interconnected to form a substation circuit, said anti-side-tone impedance network comprising four coupled inductance elements connected to form a bridge including four 55 arms and two conjugate terminals, a transformer including a primary winding normally coupled to said transmitter and a secondary winding coupled to said conjugate terminals, whereby currents traversing said secondary winding divide and traverse two of the arms of said bridge in opposite directions, said anti-side-tone impedance network including another inductance element inductively coupled to said two arms of said bridge and normally coupled to said sound reproducing device, whereby audio frequency energy developed by operation of said transmitter is not delivered to said sound reproducing device, a circuit including two arms of said bridge and the conductors of said line for conducting energizing current from said source to said transmitter, said last-named circuit also including a network for preventing audio frequency energy developed by operation of said transmitter from being delivered to said line over said last-named circuit, an auxiliary sound reproducing unit including an amplifier, said amplifier comprising a vacuum tube having input electrodes, a second 60 amplifier having output terminals and including a vacuum tube having input electrodes coupled to said transmitter, a relay operative to substitute said auxiliary sound reproducing unit for said sound reproducing device in said substation circuit, said relay also being operative to couple the output terminals of said second amplifier to the primary winding of said transformer, whereby said second amplifier and said anti-side-tone impedance network are conditioned to deliver 65 audio frequency energy developed by operation of said transmitter to said line, said relay having a winding, and circuits individual to said tubes and commonly including said winding for impressing a biasing voltage between the input electrodes of at least one of said tubes.

70 7. A telephone substation adapted to be connected to a telephone line comprising a pair of conductors arranged to have a source of direct

livered to said line over said last-named circuit, an auxiliary sound reproducing unit including an amplifier, said amplifier comprising a vacuum tube having input electrodes, a second amplifier 5 having output terminals and including a vacuum tube having input electrodes coupled to said transmitter, a relay operative to substitute said auxiliary sound reproducing unit for said sound reproducing device in said substation circuit, said 10 relay also being operative to couple the output terminals of said second amplifier to the primary winding of said transformer, whereby said second amplifier and said anti-side-tone impedance network are conditioned to deliver audio frequency 15 energy developed by operation of said transmitter to said line, power supply apparatus including an input circuit, a switch operable to complete said input circuit, said relay including a winding connected and arranged to be energized in response 20 to the completion of said input circuit, and circuits individual to said tubes and commonly including said winding for impressing a biasing voltage between the input electrodes of each of said tubes.

25 7. A telephone substation adapted to be connected to a telephone line comprising a pair of conductors arranged to have a source of direct current connected thereto and comprising, in combination, a transmitter, a sound reproducing device and an anti-side-tone impedance network arranged to be interconnected to form a substation circuit, said anti-side-tone impedance network comprising a plurality of impedance elements and being operative to prevent audio frequency energy developed by operation of said transmitter from being delivered to said sound reproducing device, a circuit including a portion of said impedance elements and the conductors of said line for conducting energizing current 30 from said source to said transmitter, said circuit also including a network for preventing audio frequency energy developed by operation of said transmitter from being delivered to said line over said circuit, additional means including said anti-side-tone impedance network for delivering audio frequency energy developed by operation of said transmitter to said line, an auxiliary sound reproducing unit comprising an amplifier, said amplifier comprising a vacuum tube having input electrodes, a relay operative to substitute said auxiliary sound reproducing unit for said sound reproducing device in said substation circuit, power supply apparatus including an input circuit, a switch operable to complete said input circuit, said relay including a winding adapted to be energized in response to the completion of said input circuit, and a circuit including said winding for impressing a biasing voltage between the input 35 electrodes of said vacuum tube.

40 10. A telephone substation adapted to be connected to a telephone line comprising a pair of conductors arranged to have a source of direct current connected thereto and comprising, in combination, a transmitter, a sound reproducing device and an anti-side-tone impedance network arranged to be interconnected to form a substation circuit, said anti-side-tone impedance network comprising four coupled inductance 45 elements and the conductors of said line for conducting energizing current from said source to said transmitter, said circuit also including a network for preventing audio frequency energy developed by operation of said transmitter from being delivered to said line over 50 said circuit, additional means including said anti-side-tone impedance network for delivering audio frequency energy developed by operation of said transmitter to said line, an auxiliary sound reproducing unit comprising an amplifier, said amplifier comprising a vacuum tube having input electrodes, a relay operative to substitute said auxiliary sound reproducing unit for said sound reproducing device in said substation circuit, power supply apparatus including an input circuit, a switch operable to complete said input circuit, said relay including a winding adapted to be energized in response to the completion of said input circuit, and a circuit including said winding for impressing a biasing voltage between the input electrodes of said vacuum tube.

45

55

8. A telephone substation adapted to be connected to a telephone line comprising a pair of conductors arranged to have a source of direct current connected thereto and comprising, in combination, a transmitter, a sound reproducing device and an anti-side-tone impedance network arranged to be interconnected to form a substation circuit, said anti-side-tone impedance network comprising a plurality of impedance elements and being operative to prevent audio frequency energy developed by operation of said transmitter from being delivered to said sound reproducing device, a circuit including a portion of said impedance elements and the conductors of said line for conducting energizing current from said source to said transmitter, said circuit also including a network for preventing audio frequency energy developed by operation of said transmitter from being delivered to said line over said circuit, additional means including said anti-

side-tone impedance network for delivering audio frequency energy developed by operation of said transmitter to said line, an auxiliary sound reproducing unit comprising an amplifier, said amplifier comprising a vacuum tube having input electrodes, a relay operative to substitute said auxiliary sound reproducing unit for said sound reproducing device in said substation circuit, said relay having a winding, and a circuit including said winding for impressing a biasing voltage between the input electrodes of said vacuum tube. 5 10

9. A telephone substation adapted to be connected to a telephone line comprising a pair of conductors arranged to have a source of direct current connected thereto and comprising, in combination, a transmitter, a sound reproducing device and an anti-side-tone impedance network arranged to be interconnected to form a substation circuit, said anti-side-tone impedance network comprising a plurality of impedance elements and being operative to prevent audio frequency energy developed by operation of said transmitter from being delivered to said sound reproducing device, a circuit including a portion of said impedance elements and the conductors of said line for conducting energizing current from said source to said transmitter, said circuit also including a network for preventing audio frequency energy developed by operation of said transmitter from being delivered to said line over said circuit, additional means including said anti-side-tone impedance network for delivering audio frequency energy developed by operation of said transmitter to said line, an auxiliary sound reproducing unit comprising an amplifier, said amplifier comprising a vacuum tube having input electrodes, a relay operative to substitute said auxiliary sound reproducing unit for said sound reproducing device in said substation circuit, power supply apparatus including an input circuit, a switch operable to complete said input circuit, said relay including a winding adapted to be energized in response to the completion of said input circuit, and a circuit including said winding for impressing a biasing voltage between the input electrodes of said vacuum tube.

10. A telephone substation adapted to be connected to a telephone line comprising a pair of conductors arranged to have a source of direct current connected thereto and comprising, in combination, a transmitter, a sound reproducing device and an anti-side-tone impedance network arranged to be interconnected to form a substation circuit, said anti-side-tone impedance network comprising four coupled inductance elements connected to form a bridge including four arms and two conjugate terminals, a transformer including a primary winding normally coupled to said transmitter and a secondary winding coupled to said conjugate terminals, whereby currents traversing said secondary winding divide and traverse two arms of said bridge in opposite directions, said anti-side-tone impedance network including another inductance element inductively coupled to said two arms and normally coupled to said sound reproducing device, whereby audio frequency energy developed by operation of said transmitter is not delivered to said sound reproducing device, a circuit including two arms of said bridge and the conductors of said line for conducting energizing current from said source to said transmitter, said last-named circuit also including a network for preventing audio frequency energy developed by operation of said transmitter from being delivered 50 55 60 65 70 75

by way of said last-named circuit to said line, additional means including said anti-side-tone impedance network for delivering audio frequency energy developed by operation of said transmitter to said line, an auxiliary sound reproducing unit comprising an amplifier, said amplifier comprising a vacuum tube having input electrodes, a relay operative to substitute said auxiliary sound reproducing unit for said sound reproducing device in said substation circuit, and means including said relay for impressing a biasing voltage between the input electrodes of said vacuum tube.

11. A telephone substation adapted to be connected to a telephone line comprising a pair of conductors arranged to have a source of direct current connected thereto and comprising, in combination, a transmitter, a sound reproducing device and an anti-side-tone impedance network arranged to be interconnected to form a substation circuit, said anti-side-tone impedance network comprising four coupled inductance elements connected to form a bridge including four arms and two conjugate terminals, a transformer including a primary winding normally coupled to said transmitter and a secondary winding coupled to said conjugate terminals, whereby currents traversing said secondary winding divide and traverse two arms of said bridge in opposite directions, said anti-side-tone impedance network including another inductance element inductively coupled to said two arms and normally coupled to said sound reproducing device, whereby audio frequency energy developed by operation of said transmitter is not delivered to said sound reproducing device, a circuit including two arms of said bridge and the conductors of said line for conducting energizing current from said source to said transmitter, said last-named circuit also including a network for preventing audio frequency energy developed by operation of said transmitter from being delivered by way of said last-named circuit to said line, additional means including said anti-side-tone impedance network for delivering audio frequency energy developed by operation of said transmitter to said line, an auxiliary sound reproducing unit comprising an amplifier, said amplifier comprising a vacuum tube having input electrodes, a relay operative to substitute said auxiliary sound reproducing unit for said sound reproducing device in said substation circuit, said relay having a winding, and a circuit including said winding for impressing a biasing voltage between the input electrodes of said vacuum tube.

12. A telephone substation adapted to be connected to a telephone line comprising a pair of conductors arranged to have a source of direct current connected thereto and comprising, in combination, a transmitter, a sound reproducing device and an anti-side-tone impedance network arranged to be interconnected to form a substation circuit, said anti-side-tone impedance network comprising four coupled inductance elements connected to form a bridge including four arms and two conjugate terminals, a transformer including a primary winding normally coupled to said transmitter and a secondary winding coupled to said conjugate terminals, whereby currents traversing said secondary winding divide and traverse two arms of said bridge in opposite directions, said anti-side-tone impedance network including another inductance element inductively coupled to said two arms and normally coupled to said sound reproducing device,

whereby audio frequency energy developed by operation of said transmitter is not delivered to said sound reproducing device, a circuit including two arms of said bridge and the conductors of said line for conducting energizing current from said source to said transmitter, said last-named circuit also including a network for preventing audio frequency energy developed by operation of said transmitter from being delivered by way of said last-named circuit to said line, additional means including said anti-side-tone impedance network for delivering audio frequency energy developed by operation of said transmitter to said line, an auxiliary sound reproducing unit comprising an amplifier, said amplifier comprising a vacuum tube having input electrodes, a relay operative to substitute said auxiliary sound reproducing device in said substation circuit, power supply apparatus including an input circuit, a switch operable to complete said input circuit, said relay including a winding adapted to be energized in response to the completion of said input circuit, and a circuit including said winding for impressing a biasing voltage between the input electrodes of said vacuum tube.

13. A telephone substation adapted to be connected to a telephone line comprising a pair of conductors arranged to have a source of direct current connected thereto and comprising, in combination, a transmitter, a circuit including the conductors of said line for conducting energizing current from said source to said transmitter, said last-named circuit comprising a network for preventing audio frequency energy developed by operation of said transmitter from being delivered by way of said last-named circuit to said line, and additional means for delivering audio frequency energy developed by operation of said transmitter to said line.

14. A telephone substation adapted to be connected to a telephone line comprising a pair of conductors arranged to have a source of direct current connected thereto and comprising, in combination, a transmitter, a circuit including the conductors of said line for conducting energizing current from said source to said transmitter, said last-named circuit comprising a low impedance alternating current by-passing and blocking network for preventing audio frequency energy developed by operation of said transmitter from being delivered by way of said last-named circuit to said line, and additional means for delivering audio frequency energy developed by operation of said transmitter to said line.

15. A telephone substation adapted to be connected to a telephone line comprising a pair of conductors arranged to have a source of direct current connected thereto and comprising, in combination, a transmitter, a sound reproducing device and an anti-side-tone impedance network arranged to be interconnected to form a substation circuit, said anti-side-tone impedance network comprising a plurality of impedance elements and being operative to prevent audio frequency energy developed by operation of said transmitter from being delivered to said sound reproducing device, a circuit including a portion of said impedance elements and the conductors of said line for conducting energizing current from said source to said transmitter, said last-named circuit comprising a network for preventing audio frequency energy developed by operation of said transmitter from being delivered to said line through said last-named circuit, and

additional means including said anti-side-tone impedance network for delivering audio frequency energy developed by operation of said transmitter to said line.

16. A telephone substation adapted to be connected to a telephone line comprising a pair of conductors arranged to have a source of direct current connected thereto and comprising in combination, a transmitter, a sound reproducing device and an anti-side-tone impedance network arranged to be interconnected to form a substation circuit, said anti-side-tone impedance network comprising four coupled inductance elements connected to form a bridge including four arms and two conjugate terminals, a transformer including a primary winding normally coupled to said transmitter and a secondary winding coupled to said conjugate terminals, whereby currents traversing said secondary winding divide and traverse two arms of said bridge in opposite directions, said anti-side-tone impedance network including another inductance element inductively coupled to said two arms and normally coupled to said sound reproducing device, whereby audio frequency energy developed by operation of said transmitter is not delivered to said sound reproducing device, a circuit including two arms of said bridge and the conductors of said line for conducting energizing current from said source to said transmitter, said last-named circuit also including a network for preventing audio frequency energy developed by operation of said transmitter from being delivered by way of said last-named circuit to said line, and additional means including said anti-side-tone impedance network for delivering audio frequency energy to said line.

17. A telephone substation adapted to be connected to a telephone line and comprising, in combination, a transmitter and receiver arranged to be interconnected to form a substation circuit, an auxiliary sound reproducing unit comprising an amplifier, said amplifier including a vacuum tube having input electrodes, a relay operative to substitute said auxiliary sound reproducing unit for said receiver in said substation circuit, said relay including a winding, and a circuit including said winding for impressing a direct biasing voltage between the input electrodes of said tube when said winding is energized.

18. A telephone substation adapted to be connected to a telephone line and comprising, in combination, a transmitter and receiver arranged to be interconnected to form a substation circuit, an auxiliary sound reproducing unit comprising an amplifier, said amplifier including a vacuum tube having input electrodes, a relay operative to substitute said auxiliary sound reproducing unit for said receiver in said substation circuit, said relay including a winding, power supply apparatus including an input circuit, a switch operable to complete said input circuit, said winding being connected and arranged to be energized in response to the completion of said input circuit, and a circuit including said winding for impressing a direct biasing voltage between the input electrodes of said tube when said winding is energized.

19. A telephone substation adapted to be connected to a telephone line and comprising, in combination, a transmitter and receiver arranged to be interconnected to form a substation circuit, an auxiliary sound reproducing unit comprising an amplifier, said amplifier including a vacuum tube having input electrodes, a second amplifier

including a vacuum tube having input electrodes, a relay operative to substitute said auxiliary sound reproducing unit for said receiver in said substation circuit, said relay also being operative to include said second amplifier in said substation circuit, means including said second amplifier for delivering audio frequency energy developed through operation of said transmitter to said line, and means including said relay for impressing a biasing voltage between the input electrodes of each of said tubes.

20. A telephone substation adapted to be connected to a telephone line and comprising, in combination, a transmitter and receiver arranged to be interconnected to form a substation circuit, an auxiliary sound reproducing unit comprising an amplifier, said amplifier including a vacuum tube having input electrodes, a second amplifier including a vacuum tube having input electrodes, a relay operative to substitute said auxiliary sound reproducing unit for said receiver in said substation circuit, said relay also being operative to include said second amplifier in said substation circuit, means including said second amplifier for delivering audio frequency energy developed through operation of said transmitter to said line, said relay including a winding, and circuits individual to said tubes and commonly including said winding for impressing a biasing voltage between the input electrodes of each of said tubes.

21. A telephone substation adapted to be connected to a telephone line and comprising, in combination, a transmitter and receiver arranged to be interconnected to form a substation circuit, an auxiliary sound reproducing unit comprising an amplifier, said amplifier including a vacuum tube having input electrodes, a second amplifier including a vacuum tube having input electrodes, a relay operative to substitute said auxiliary sound reproducing unit for said receiver in said substation circuit, said relay also being operative to include said second amplifier in said substation circuit, means including said second amplifier for delivering audio frequency energy developed through operation of said transmitter to said line, said relay including a winding, power supply apparatus including an input circuit, a switch operable to complete said circuit, said winding being connected and arranged to be energized in response to the completion of said input circuit, and circuits individual to said tubes and commonly including said winding for impressing a biasing voltage between the input electrodes of each of said tubes.

22. A telephone substation adapted to be connected to a telephone line and comprising, in combination, a transmitter and receiver arranged to be interconnected to form a substation circuit, an amplifier including a vacuum tube having input electrodes, said transmitter normally being connected to transmit audio frequency energy to said line over a path from which said amplifier is excluded, a relay operative to include said amplifier in said audio frequency energy transmission path, said relay including a winding, and a circuit including said winding for impressing a direct biasing voltage between the input electrodes of said tube when said winding is energized.

23. A telephone substation adapted to be connected to a telephone line and comprising, in combination, a transmitter and receiver arranged to be interconnected to form a substation circuit, an amplifier including a vacuum tube having in-

put electrodes, said transmitter normally being connected to transmit audio frequency energy to said line over a path from which said amplifier is excluded, a relay operative to include said 5 amplifier in said audio frequency energy transmission path, power supply apparatus including an input circuit, a switch operable to complete said circuit, said winding being connected and arranged to be energized in response to the completion of said input circuit, and a circuit including said winding for impressing a direct biasing voltage between the input electrodes of said tube when said winding is energized.

24. A telephone substation adapted to be connected to a telephone line and comprising, in combination, a transmitter and receiver arranged to be interconnected to form a substation circuit, a path for directly transmitting audio frequency energy from said transmitter to said line, an 10 amplifier having input terminals coupled to said transmitter and output terminals adapted to be coupled to said line, power supply apparatus operative to deliver energizing current to said amplifier, thereby to condition said amplifier for 15 operation, an input circuit for said power supply apparatus, a switch for completing said input circuit, and means responsive to the operation of said switch for simultaneously interrupting said path and coupling said output terminals to 20 said line.

25. A telephone substation adapted to be connected to a telephone line and comprising, in combination, a transmitter and receiver arranged to be interconnected to form a substation circuit, 25 a path for directly transmitting audio frequency energy from said transmitter to said line, an amplifier having input terminals coupled to said transmitter and output terminals adapted to be coupled to said line, power supply apparatus 30 operative to deliver energizing current to said amplifier, thereby to condition said amplifier for operation, an input circuit for said power supply apparatus, a switch for completing said input circuit, and a relay operative simultaneously to interrupt said path and to couple said 35 output terminals to said line, said relay including a winding connected and arranged to be energized in response to the completion of said input circuit.

26. A telephone substation adapted to be connected to a telephone line and comprising, in combination, a transmitter and a receiver arranged to be interconnected to form a substation circuit, an auxiliary sound reproducing unit, a switch operable from a normal position to an off-normal position, means responsive to the operation of said switch to said off-normal position for substituting said auxiliary sound reproducing unit for said receiver in said substation 10 circuit, a low impedance path normally shunting said transmitter, a second switch operable from a normal position to an off-normal position, means responsive to the operation of said second switch to said off-normal position for interrupting said low impedance path, and means responsive to the operation of said first-named switch from its off-normal position to its normal position for operating said second switch from its off-normal position to its normal position. 15

27. A telephone substation adapted to be connected to a telephone line and comprising, in combination, a transmitter, a receiver and an anti-side-tone impedance network arranged to be interconnected to form a substation circuit, said anti-side-tone impedance network being operative to prevent audio frequency energy developed by operation of said transmitter from being delivered to said sound reproducing device, an auxiliary sound reproducing unit, a switch operable from a normal position to an off-normal position, means responsive to the operation of said switch to said off-normal position for substituting said auxiliary sound reproducing unit for said receiver in said substation circuit 20 and for creating a calling condition on said line, a low impedance path normally shunting said transmitter, a second switch operable from a normal position to an off-normal position, means responsive to the operation of said second switch to its off-normal position for interrupting said low impedance path, and means responsive to the operation of said first-named switch from its off-normal position to its normal position for operating said second switch from its off-normal 25 position to its normal position. 30
